WILLIAM G. CREAMER, OF BROOKLYN, NEW YORK.

Letters Patent No. 94,872, dated September 14, 1869.

HOT-AIR REGISTER.

The Schedule referred to in these Letters Patent and making part of the same.

To all whom it may concern:

Be it known that I, WILLIAM G. CREAMER, of Brooklyn, county of Kings, State of New York, have invented a new and improved Mode of Constructing Hot-Air Registers; and I do hereby declare that the following is a full and exact description thereof, reference being had to the accompanying drawings, and to the letters of reference marked thereon.

The nature of my invention consists in so constructing hot-air registers (such as are used in connection with hot-air furnaces for warming buildings,) as to make them adjustable and fixed at any point that may be desired.

I have found, by experience, that the registers that are now made are very uncertain, with reference to making them stay at any desired point. They must, necessarily, move easily. The register may be closed tight, and a person or persons walking over it will jar it open; or it may be open, and it will be accidentally closed by the same causes. They cannot be adjusted so as to allow a slight current of hot air to enter the room, and remain so with certainty. I have often noticed that persons, while standing on the registers to warm their feet, will touch the star-centre, or the corrugated wheel at the end, and thus unconsciously close, or partially close it, when not desired.

My invention makes the adjustment, at any desired point, an absolute certainty.

To enable others skilled in the art to make and use my invention, I will proceed to describe its construction and operation.

I make my registers of the usual form, of any desired design, or similar to that shown at plate 1 of the accompanying drawings.

Underneath this screen, I affix a box, or frame of iron, plates 2 and 3.

In the bottom of this are fitted the valves or blinds, plate 5, letter Q, and plate 3, letters Q Q Q.

The blinds are then connected together by a slat, letter N, plate 3 and plate 7.

To this slat is again attached a connecting-rod, S, which again connects with the adjustable lever, plate 9, P M.

The fulcrum of this lever is underneath the screen, plate 1, letter R.

At the short end of the lever, letter M, the attachment is made that works the blinds, by the connecting-rod S.

At the long end of the lever is attached a brass knob, letter P.

This knob traverses in the arc S T, plate 1, of the screen. The brass knob is in a recess of the screen, below the surface, and the lever is under the screen.

To open the valves, the knob is pushed to the point S, plate 1. To close the valves, it is pushed toward the point T, plate 1. To adjust the valves at any desired point, a turn of the knob runs the lever P M close up, and secures it to the under side of the screen.

It will thus be seen that the valves can be easily and quickly adjusted and fixed at any desired place, with a certainty of their remaining so.

Plate 11 is simply a cast plate, that is riveted at each end of the box, plate 2, and in which the pivots of the valves are fitted.

What I claim as my invention, and desire to secure by Letters Patent, is—

The construction of a register for the discharge of hot air, in such a way that the valves may be adjusted and fixed at any desired point, substantially as described, and for the purposes mentioned.

WM. G. CREAMER.
